ROOM THERMOSTAT ENCLOSURE

Walter W. Hoyle, 122 Cashin Drive,
Fayetteville, N.Y. 13066

Filed Oct. 21, 1968, Ser. No. 14,082

Term of patent 14 years

Int. Cl. D10—07

U.S. Cl. D52—7

FIG. 1

FIG. 2

FIG. 3

FIGURE 1 is a front elevational view of a room thermostat enclosure embodying my new design;

FIGURE 2 is a bottom elevation of the unit in FIGURE 1; and

FIGURE 3 is an end elevational view thereof.

I claim:

The ornamental design for a room thermostat enclosure, substantially as shown and described.
